RICHARD H. STEVENS, OF MUNHALL, PENNSYLVANIA, ASSIGNOR OF
ONE-HALF TO PER TORSTEN BERG, OF STOCKHOLM, SWEDEN.

DUMPING-CAR.

No. 802,532.

Specification of Letters Patent.

Patented Oct. 24, 1905.

Application filed June 9, 1905. Serial No. 264,431.

To all whom it may concern:

Be it known that I, RICHARD H. STEVENS, of Munhall, Allegheny county, Pennsylvania, have invented a new and useful Dumping-Car, 5 of which the following is a full, clear, and exact description, reference being had to the accompanying drawings, forming part of this specification, in which—

Figure 1 is a sectional end elevation showing a ladle-car provided with one form of my invention. Fig. 2 is a partial side elevation of the same.

My invention relates to dumping-cars which are tipped in either direction, more especially 15 to ladle-cars.

The object of the invention is to provide connections by which a stationary motor may tilt the car in either direction, and, further, to provide simple and efficient means for holding 20 the car in vertical position.

In the drawings, 2 represents the ladle supported at its ends upon trunnions 3, to which are keyed gear-wheels 4, meshing with stationary racks 5 upon the end frame of the car. 25 The motor which tips the car is applied at one end only and in this form consists of a pneumatic, steam, or hydraulic cylinder 6, rigidly secured to the framing. The piston-rod 7 of this double-acting cylinder is secured at its 30 outer end to a cross-head 8, having two lower integral tubular guides 9, which slide over two guide-rods 10. These guide-rods are secured to their outer ends to the stationary bracket 11, and their other ends rest in holes in station- 35 ary brackets or lugs 12.

A rack 13, having teeth 14, which mesh with the teeth in the gear-wheel 4, is pivoted at one end to the upper end of the cross-head 8. The rack is normally in mesh with gear-wheel 4, 40 but may be lifted and held with its teeth out of engagement with the gear-wheel 4 by means of an idler-roller 15 in the longitudinal slot 16 in the rack. The idler-roller 15 is eccentrically mounted on the shaft 16', which is carried 45 in bearings on the bracket 17, mounted on the end of the cylinder 6. The rack 13 is lifted into and out of engagement with the teeth on the gear-wheel 4 by means of a hand-lever 18 on the end of the eccentric-shaft 16', and the 50 movement of said lever is limited by the stops 19 on the bracket 17.

With the parts connected as shown in Fig. 1 when fluid is admitted to the right-hand end

of the cylinder it will exert a push action through the cross-head upon the movable rack 55 connection to the gear-wheel, and thus tilt the ladle in a counter-clockwise direction until the ladle-body strikes the side frame member 20, which acts as a stop. The ladle is tilted back to normal position by admitting fluid to the 60 other end of the cylinder in the usual manner. If it is desired to tilt the ladle in a clockwise direction, the movable rack 13 is raised by means of the lever 18 until the teeth in the 65 rack are out of engagement with the teeth in the gear-wheel 4. Fluid is admitted to the cylinder to move the rack until the teeth near the pivotal end of the rack are above the gear-wheel 4. The position of the hand-lever 18 is then reversed, and the teeth of the 70 rack are brought into engagement with the teeth of the gear-wheel, the piston then being at or near the left-hand end of the cylinder. Now if fluid is admitted to the left-hand end of the cylinder it will pull upon the 75 rack 13 and swing the ladle in a clockwise direction until the ladle-body strikes the frame 20 on its side. The tilting to normal position will be carried out by admitting fluid to the right-hand end of the cylinder. In both cases 80 the stroke of the piston is less than the length of the cylinder, which stopping at an intermediate point in the length of the cylinder when the ladle strikes is stopped by the frame 20 in its downward movement. 85

In order to lock the ladle in upright position when arranged for tilting in either direction, I provide a spacing-collar 21 upon the guide-rod 10, and upon a locking-rod 22, mounted in bearings 23 on the frame, I provide 90 two latches or pawls 24. These latches are rigidly secured to the locking-rod and their bottom portions are shaped as shown in Fig. 2, so that when they are swung forward they will rest in line with the guide 9. The 95 depending bent handles 22 then hold them in this position. In the position shown in Fig. 1 the ladle is locked in vertical position by the collar 9, which is held between the stationary bracket 11 and the latch 24. When 100 arranged for tilting in the opposite direction, the collar 9 will be similarly held between the spacer 21 and the other pawl 24 near the central portion of the rod 22. The ladle is unlocked in either position by turning the rod 105 through either handle 22.

Instead of using a motive cylinder I may employ gearing or actuating connections for moving the cross-head.

The advantages of my invention result from 5 the simplicity of the device and the ease of changing it for tilting in either direction. The stationary portion of the motor is stationary at all times and is not shifted in changing the direction of tilting.

10 Another advantage of my construction is that the pressure is applied to the gear-wheel at a point above the axis of rotation, so that a longer lever-arm is obtained, enabling a smaller motor to be used.

15 The apparatus may be applied to existing ladle-cars and is efficient and economical.

Where a motor-cylinder is employed, the piston may be stationary and the cylinder movable, and many other changes may be 20 made in the form and arrangement of the motor and connections without departing from my invention.

I claim—

1. A tipping car having a stationary motor, 25 a cross-head actuated thereby, and a movable rack connected with the cross-head and having teeth engaging with the teeth of a gear-wheel on the trunnion; substantially as described.

30 2. A tipping car having a motor with its stationary portion stationary at all times, the movable portion of the motor having a rack adapted to tilt the car by engagement with a gear-wheel on the car, and means for adjusting 35 the rack to different relative positions with the gear-wheel, while the stationary motor portion remains in a fixed position; substantially as described.

3. A rolling and tipping car having a motor 40 with its stationary part stationary at all times, the movable portion of the motor having a rack arranged to tilt the car, and means for adjusting the rack to different relative positions with the gear-wheel; substantially as described.

45 4. A tipping car having a movable cross-head, a movable rack pivoted to the cross-head and having a plurality of points of connection to the gear-wheel on the trunnion, and 50 means for moving the cross-head endwise; substantially as described.

5. A tipping car having a movable cross-head, a rack pivoted to the cross-head and

having a plurality of points of connection to the gear-wheel on the trunnion, means for 55 moving the cross-head endwise, and means for locking the car-body in vertical position; substantially as described.

6. A tilting car or ladle having a guiding-rack connected to its trunnions above the axis 60 of rotation; substantially as described.

7. A rolling and tilting ladle supported on trunnions, a rack connected to one of the trunnions means for moving the rack into and out of engagement with the trunnion, and a motor arranged to either push or pull the rack without shifting the stationary portion of the motor; substantially as described.

8. A ladle-car having a trunnioned ladle, a motive cylinder having one part stationary and a movable bar connected to a cross-head and a rack extending from the cross-head and having shiftable connection with the trunnions, the stationary part of the motor remaining in its fixed position during the shifting 75 of the rack connection; substantially as described.

9. A ladle-car having a motive cylinder with one element stationary, a cross-head connected to the movable element, a rack pivoted to the 80 cross-head and a shifting device for moving the rack into and out of engagement with the trunnion; substantially as described.

10. A car having a tilting ladle mounted on trunnions, a motive cylinder having one element stationary at all times, a cross-head connected to its movable element, a rack connected to the cross-head and engaging with the trunnion above its center of rotation, and a shifting device for moving said rack into 85 and out of engagement with the trunnion; 90 substantially as described.

11. A tipping car having a trunnion provided with a gear-wheel, a motor, a rack connected with the motor and arranged to intermesh with the gear-wheel, and mechanism for moving the rack into and out of mesh with the gear-wheel to intermesh the same in different positions; substantially as described.

In testimony whereof I have hereunto set 100 my hand.

RICHARD H. STEVENS.
